ELISHA N. FALES, OF DAYTON, OHIO

DEVICE FOR IMPROVING THE AERODYNAMIC EFFICIENCY OF AN EXHAUSTER FAN

Application filed June 9, 1923. Serial No. 644,517.

This invention relates in general to exhauster fans and more particularly to a device for improving the aerodynamic efficiency of an exhauster fan.

5 It is common practice to place exhauster fans in round holes cut into the wall of the room or space to be ventilated. A fan so mounted propels the blast of exhausted gas at a high velocity outward from the opening 10 in the wall, the kinetic energy of the blast being lost. Furthermore, in such a fan mounting, there is formed a ring of reverse flow of gas just down stream of the blade tips, this ring of reverse flow being of an interior diameter slightly less than that of the fan. This reverse flow and high velocity discharge blast represent unutilized energy.

It is the prime object of my invention to provide a means for mounting an exhauster 20 fan such that part of the energy due to the high velocity blast discharge and reverse flow shall be utilized in assisting the action of its exhauster fan.

The construction of my device will be 25 made clear in the accompanying specification and claims and will be disclosed in the accompanying drawings in which:

Fig. 1 is a side elevation largely in section of my device.

30 Figure 1—A is a diagrammatic view illustrating the mathematical basis for the curvature of the acceleration cone 2 and flared lip portion 6 of the fluid duct.

Fig. 2 is a similar view of a modification of 35 the device shown in Fig. 1 and especially providing fan motor mounting means.

Fig. 3 is a similar view of another modification of my device.

Figure 4 is a diagrammatic view of a simple 40 fan showing the typical air flow when in operation.

Figure 5 is a similar view showing the air flow when the fan is completely contained within an air duct.

45 Figure 6 is a similar view showing the effect of mounting at the delivery end of the fan an air duct having its inlet end smaller in diameter than the fan.

Referring with greater particularity to the 50 drawings, particular reference being had first

to Fig. 1, it will be noted that I mount my exhauster fan 1 at a point away from the wall 3 and inside the space to be exhausted.

An orifice of a diameter less than that of the fan is cut in the wall 3 of the room to 55 be ventilated.

An acceleration cone 2 is fitted on the inside of the wall concentric with the above orifice, said cone having its minimum circumference coincident with the inner circumference of 60 said orifice, said acceleration cone having a flange 4 extending in a plane parallel with the inner surface of the wall and being adapted to be secured to the walls by suitable retaining means 5. This cone 2 has its intake end 65 flared back to form a lip as shown at 6 to provide a guideway to conduct the reverse flow of gas, as indicated by the arrows $r-r$ into the area of the fan blade tips and downstream thereof. It will be noted that the outer diameter of the cone 2 is slightly less than that of the fan to permit the useful employment of 70 this reverse flow of gases. The curvature of this flared portion must be carefully computed to attain the maximum efficiency. 75

The formula for the curvature of the lip portion 6 and the acceleration cone 2 of the fluid duct is as follows:

$$Y = .45D \pm \frac{\sqrt{.8DX - X^2}}{8}$$

Referring to Figure 1—A, it will be observed that in constructing the curve from the above formula, it is assumed that the X axis is coincident with the rotational axis of the fan proper and that the Y axis lies in the plane of the lip portion of the fluid duct, where the acceleration cone merges with the flared lip. In the formula, D represents the propeller tip diameter and .45D represents the radius of the line of merger of the cone 2 and lip 6. The plus sign is used before the radical in computing curvature of the flared lip 6, whereas the minus sign is used when curvature of the acceleration cone 2 is to be determined. Values of X should not exceed .8D. 85 90 95

A deceleration cone 7 is mounted on the outer side of the wall, its minimum circumference being coincident with the orifice in

the wall. Cone 7 is similarly provided with a flange 8 and adapted to be secured to the wall by securing means 5. The deceleration cone, together with the acceleration cone, forms a Venturi shaped duct and the high velocity blast is thus utilized to increase the exhausting capacity of the fan. In the type 5 illustrated in this figure the exhauster fan may be mounted in any suitable manner and brought into proximity thereto as illustrated.

10 In the modification shown in Fig. 2 I have provided a bracket 10 to support the conventional wall type ring 11, the fan motor 12 and the fan 1 itself. Otherwise the structure 15 is similar in every particular to that shown in Fig. 1.

Fig. 3 discloses flared portion 6 as curved 20 backward to the wall thus providing for greater rigidity of mounting and a longer curved guideway for the reverse flow.

25 A bracket 15 is also provided as a support for the exhaust fan and its motor.

The construction of my invention having 30 been described its operation will be seen to be as follows: The acceleration cone having an inlet end of slightly less diameter than that of the fan, and having its inlet end provided with a curved flare, as described, to form a guideway, utilizes the effect of the reverse flow adjacent the fan blade tips. The deceleration cone and acceleration cone form a 35 Venturi duct with its minimum diameter at the wall of the building to be ventilated, which Venturi duct enables the kinetic energy 40 of the exhaust blast to assist the fan in exhausting gas from the room which it is designed to ventilate.

Explanation of the action of the invention 45 may be amplified by considering, first, the airflow produced by a simple fan, next, the airflow of a fan mounted in the usual manner entirely within an air duct, and, finally, the air-flow created by the use of my improved form of duct and guiding surfaces.

50 Referring to Figure 4 of the drawings, it will be observed that the fan blades produce a main stream of air, or other fluid, which, as it passes between the blades, is smaller in diameter than the external diameter of the fan.

55 This main stream also tapers in its progress so that it is even smaller in diameter at a place several inches away from the delivery end of the fan. Outside the main stream, there is produced a peripheral current which is 60 reversely flowing with respect to the former at the delivery end of the fan and becomes radially inward, or centripetal, in its direction of flow in the plane of the fan. The reverse flow joins the main stream at a line, roughly speaking, designated by so-called 65 "dead points" A. The simplest demonstration of this air-flow is by holding a lighted match near the tips of the blades of a rotating desk fan at the front of the same considering the direction of flow. It will be observed that

there is no forward blast proceeding from the extreme tips of the blades and that the main stream is of smaller diameter than the fan.

70 When the radially inward flow at the tips is interfered with, which occurs when the fan is entirely contained within a cylindrical housing or duct as shown in Figure 5, the reverse flow at the tips takes the form of leakage. Furthermore, turbulence is produced along the wall of the duct surrounding the main stream.

75 The present invention embraces the proper means for curing the adverse effect on the fan efficiency produced by the reversed flow at the blade tips. It is, paradoxically, to permit the reverse flow to move backward from in front of the tips to enter the tip-circle, to receive forward impulse from the blades, and then to move forward at high velocity in the main stream of the fan blast. At the "dead points" 80 A, where no air is leaving the fan disc and where the reverse flow does not exist, a wall may be positioned adjacent to the fan and at the delivery end of the same so as to separate the reverse flow from the main stream. In 85 Figures 1 to 3 inclusive and in Figure 6, the inlet end, or mouth, of the air duct forms this proposed wall. The duct without any guiding surface at its mouth such as is shown in these figures, would increase the efficiency of 90 the fan by permitting it to deliver its whole blast without reverse-flow leakage. By providing a guiding surface surrounding the duct mouth and converging toward the fan, the reverse flow will be led in a more efficient 95 manner back into the main stream. Greatest 100 efficiency may be obtained by giving the guide surface the curvature illustrated in Figure 3. The air-flow is represented in Figures 1 and 6.

105 Carrying the inventive idea still further, the air duct has been given the form of a venturi having its throat positioned adjacent to the delivery end of the fan. The venturi does not necessarily constrict the flow from 110 the fan. As has already been stated, this flow naturally converges after it leaves the fan (when the fan is efficient) and will follow the curvature of the accelerating cone. It is obvious that a channel formed to fit the blast 115 like a glove will cause no "back-pressure." The decelerating cone facilitates the recovery of energy of the high velocity exhaust blast. The principle on which this fact is based is that of the "draft tube" in hydraulic power plants, the "blower cone chimney" in mine 120 ventilating machines, and the "decelerating cone" in aerodynamic wind tunnels. Any blast of fluid flowing through such an expanding cone, can be made to slow up gradually, due to the enlarging cross-sectional 125 area of the flow-channel. The kinetic energy of the blast is converted into pressure energy according to "Bernouilli's Theorem," i. e. that the sum of potential energy, pressure energy 130 and kinetic energy in an ideal fluid flow is

constant, and when one of these energies decreases, the others must increase, etc. Where a decelerating cone is used in the air duct for an exhaust fan, a high velocity at the small end can be converted into a low velocity at the large outlet end. The blast can be maintained for less motor power, because the motor does not have to furnish the power otherwise wasted as exhaust velocity kinetic energy. A relatively small motor will handle the same amount of air which otherwise would require a large motor. The longer the decelerating cone, the more true is the above. It will be noted that in the drawings the large end of the decelerating cone has two-thirds larger diameter than that of the throat.

I claim:

1. In a device of the class described, a rotatable exhaust fan, a member forming a fluid duct disposed with its inlet end adjacent to the fan at its delivery end and being smaller in internal diameter than the external diameter of the fan, and a tapered guiding surface provided on the outside periphery of the duct-forming member surrounding the inlet end.

2. In a device of the class described, a rotatable exhaust fan, a member forming a fluid duct disposed with its inlet end adjacent to the fan at its delivery end and being smaller in internal diameter than the external diameter of the fan, and a tapered guiding surface provided on the outside periphery of the duct-forming member surrounding the inlet end, the guiding surface being converged upstream toward the fan blades.

3. In a device of the class described, a rotatable exhaust fan, and a member forming a Venturi-shaped fluid duct disposed with the mouth of its acceleration cone adjacent to the delivery end of the fan and being smaller in internal diameter than the external diameter of the fan.

4. In a device of the class described, a rotatable exhaust fan adapted to create a central main stream of fluid moving in one direction and a peripheral reverse or radially inward flow, a member forming a Venturi-shaped fluid duct disposed with the mouth of its acceleration cone adjacent to the delivery end of the fan and smaller in internal diameter than the external diameter of the fan, and means for guiding the reverse flow of fluid centripetally toward the main stream at the mouth of the fluid duct.

5. In a device of the class described, a rotatable exhaust fan, a member forming a Venturi-shaped fluid duct disposed with the mouth of its acceleration cone adjacent to the delivery end of the fan and smaller in internal diameter than the external diameter of the fan, and a tapered guiding surface provided on the outside periphery of the duct-forming member surrounding its mouth and

being converged upstream toward the fan blades.

6. In a device of the class described, a rotatable exhaust fan adapted to create a central main stream of fluid moving in one direction and a peripheral reverse flow, a member forming a fluid duct disposed with its inlet end adjacent to the delivery end of the fan and being smaller in internal diameter than the external diameter of the fan, and a tapered guiding surface provided on the outside periphery of the duct-forming member surrounding the inlet end, the guiding surface being converged upstream toward the fan blades and being convexly curved in an axial direction to direct the reverse flow of fluid centripetally into the main stream at the inlet to the duct.

7. In a device of the class described, a rotatable exhaust fan adapted to create a central main stream of fluid moving in one direction and a peripheral reverse flow, a member forming a Venturi-shaped fluid duct disposed with the mouth of its acceleration cone adjacent to the inlet end of the fan and smaller in internal diameter than the external diameter of the fan, and a tapered guiding surface provided on the outside periphery of the duct-forming member surrounding its mouth, the guiding surface being converged upstream toward the fan blades and being convexly curved in an axial direction to direct the reverse flow of fluid centripetally into the main stream at the mouth of the duct.

In testimony whereof I affix my signature.
